Primary Examiner — Darcey E Gottschalk(74) *Attorney, Agent, or Firm* — Perkins Coie LLP(57) **CLAIM**

The ornamental design for a bottle ring with a bottle, as shown and described.

DESCRIPTION

FIG. 1 is an exploded view of a bottle ring with a bottle; FIG. 2 is an isometric view of the bottle ring of FIG. 1 when positioned on the bottle;

FIG. 3 is a frontal view of the bottle ring of FIG. 1 when positioned on the bottle;

FIG. 4 is a zoomed-in view of the isometric view of the bottle ring of FIG. 1 shown removed from the bottle for clarity of disclosure;

FIG. 5 is a top view of the bottle ring of FIG. 4;

FIG. 6 is a frontal view of the bottle ring of FIG. 4; and, FIG. 7 is a cross-sectional view of the bottle ring of FIG. 4 along the plane identified in FIG. 5.
